US0D1088340S

(12) **United States Design Patent** (10) **Patent No.:** **US D1,088,340 S**
(45) **Date of Patent:** **** Aug. 12, 2025**

(54) **CONTAINER WITH CHILDPROOF LID**

(71) Applicant: **DIZPOT LLC**, Phoenix, AZ (US)

(72) Inventor: **Cassandra Lynn**, Phoenix, AZ (US)

(73) Assignee: **DIZPOT LLC**, Phoenix, AZ (US)

(**) Term: **15 Years**

(21) Appl. No.: **29/886,788**

(22) Filed: **Mar. 13, 2023**

(51) **LOC (15) Cl.** **27-06**

(52) **U.S. Cl.**

(57) **CLAIM**

The ornamental design for container with childproof lid as shown and described.

DESCRIPTION

FIG. 1 illustrates a top perspective view of a container with childproof lid;

FIG. 2 illustrates a lower perspective view thereof;

FIG. 3 illustrates a front plan view thereof;

FIG. 4 illustrates a rear plan view thereof;

FIG. 5 illustrates a right side view thereof;

FIG. 6 illustrates a left side view thereof;

FIG. 7 illustrates a top plan view thereof;

FIG. 8 illustrates a bottom plan view thereof; and,

FIG. 9 illustrates a side cross-sectional view thereof.

The broken lines shown in the drawings represent portions of the container with childproof lid that form no part of the claimed design.

1 Claim, 8 Drawing Sheets
